UNITED STATES PATENT OFFICE.

ANDREW H. CANDEE, OF PITTSBURGH, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed August 5, 1919. Serial No. 315,445.

To all whom it may concern:

Be it known that I, ANDREW H. CANDEE, a citizen of the United States, and a resident of Pittsburgh, in the county of Allegheny and State of Pennsylvania, have invented a new and useful Improvement in Control Apparatus, of which the following is a specification.

My invention relates to control apparatus, and it has special relation to unit switches or contactors of the electro-pneumatic type.

One object of my invention is to provide a switching device of the above indicated character which shall be relatively compact in construction and light in weight, and which shall embody a relatively small number of parts.

More specifically stated, it is the object of my invention to provide a novel actuating and supporting mechanism for the movable contact member, whereby a direct pivotal connection thereof to the reciprocating power element, such as the piston member, is provided and a combined rolling and wiping contact between the movable and the stationary contact tips is effected.

Another object of my invention is to provide an integral projection of the movable contact member to supplement the action of the customary arcing horn and to prevent flare-back toward the grounded portion of the switching device.

A further object of my invention is to provide a novel means for supporting the magnetic blow-out coil, including the use of the pole-pieces for the double function of providing the desired magnetic circuit and also serving to support the blow-out coil.

Other objects of my invention, directed toward compactness of structure and lightness of weight, will become evident from the following detailed description, taken in conjunction with the accompanying drawing, wherein Figure 1 is a view, partially in elevation and partially in vertical section, of a switching device constructed in accordance with my present invention; Fig. 2 is a view in front elevation thereof; Fig. 3 and Fig. 4 are detail views of a portion of my switching device, Fig. 3 being a sectional view taken on the line III-III of Fig. 4; Fig. 5, Fig. 6 and Fig. 8 are detail views of another member of my switching device, Fig. 8 being a sec-

tional view taken on the line VIII-VIII 55 of Fig. 5; and Figs. 7, 9 and 10 are elevational views of another member of the switching device.

Referring to the drawings, the structure here shown comprises a base or supporting panel 1 that is adapted to be mounted preferably in a vertical position, and to which is secured an upper contact support 2, an insulating terminal support 3 and an actuating-mechanism support 4. The device 60 further comprises a stationary contact member 5, a co-operating movable contact mechanism 6, a magnetic blow-out coil device 7, an arc-chute apparatus 8, a pneumatic actuating mechanism 9 and an electrically-70 controlled valve 10 for governing the actuating mechanism 9.

The upper contact support 2 is rigidly secured to the upper part of the base 1 by means of a plurality of bolts 15, and is 75 pierced by a transversely extended bolt 16 for securing one terminal of the blow-out coil device 7 to the metallic support 2.

The insulating disk 3 is secured to an intermediate part of the base 1 through the 80 agency of a suitable bolt 17, which is adapted to support one of the external wire-receiving terminals for the switching device, as hereinafter described in detail.

The actuating-mechanism support 4 is secured to the lower part of the base 1 by 85 means of a plurality of bolts 18, whereby a single casting including both the pneumatic cylinder and the controlling valve therefor, is properly positioned.

The stationary contact member 5 comprises a bent tip 19 of a familiar form, the shorter arm of which is secured within a rectangular recess in the upper contact support 2 by means of a bolt 20, which also 95 serves to maintain in position a curved arcing horn 21 of a well-known type.

The movable contact mechanism 6 comprises a similar contact tip 22 that is secured to a supporting member 23 (shown 100 also in Fig. 3 and Fig. 4) by means of a bolt 24, which also serves to position the lower arcing horn 25. A pivot or pin 26 extends transversely through a portion of the support 23 remote from the contact tip 105 22, this pin 26 being supported in a stationary bracket or standard 27 (shown also in Figs. 5, 6 and 7), which is rigidly as-

sociated with the piston of the operating mechanism 9, as hereinafter more fully set forth.

The lower contact support 23, in addition to being provided with an opening 24^a for receiving the bolt 24 and for also receiving one end of a coil spring 43, as subsequently set forth in detail, is provided with an integral extension or bent tip 28 which extends substantially parallel to the contacting surface of the movable contact tip 22, for the purpose of preventing flare-backs of arcs to the lower portions of the switch, these arcs being formed by the separation 18 of the stationary and the movable contact tips 19 and 22, respectively. A depending lug 29 upon the face of the support 23 near the base 1, is employed for locking with the contact bracket 27 for a purpose to be set forth.

The contact bracket 27 comprises a plurality of parallel-extending arms 34 and 35 (see Fig. 6) through which the pin 26 passes and a web 36 extending between these arms 25 for a certain distance, the web being omitted from the uppermost portion of the bracket to permit the contact support 23 to be also mounted upon the pivot 26. The web 36 is provided with an aperture 37 for a purpose 30 to be explained later, and the lower horizontally-extending plate or base of the bracket 27 is provided with a plurality of bolt-receiving openings 38 and 39, whereby the bracket 27 is rigidly assembled with the reciprocatory power element or piston stem of the actuating mechanism 9.

A wing or ear 40 in the plane of the bracket base extends transversely to the supporting arms 34 and 35, and is provided 40 with a bolt-receiving opening 41, whereby a wire-receiving terminal 47 may be mechanically attached to the bracket through the agency of a bolt 42. This terminal 47 is electrically secured to a braided cable or 45 shunt 46 which first passes beneath the terminal 47, and then extends upwardly to a second terminal 48, which is bolted to a main terminal 44 of the switching device, by means of the bolt 17 and suitable locking nuts 45.

The contact bracket 27 is secured to an insulating block 32 by means of bolts 33 extending through the openings 38 and 39.

A plug 49 is inserted in the opening 37 in 55 the web 36 of the contact bracket 27, and the spring 43 has its ends respectively enclosing the plug 49 and located within the recess 24^a of the contact support 23. It should be noted that the upper edge of the web 36 60 engages the depending lug 29 of the support 23 to restrict the biasing action of the spring 43 on the movable contact tip 22.

The blow-out coil device 7 comprises a suitable coil 50, preferably of strap conductor, having a plurality of convolutions

wound around a suitable core member 51, one end-connector or terminal 52 of the coil 50 extending from the inner convolution thereof and comprising an end-portion of the strap conductor which is bolted to the 70 upper contact support 2 by means of the bolt 16. The other end-connector of the blow-out coil extends toward the front of the switching device from the outer convolution of the coil and a suitable terminal 53 75 for the switching device, as a whole, is bolted to such end-connector.

The path of current through the switching device, when closed, may thus be traced from the terminal 53 through the convolutions of the blow-out coil 50 and connector 52, upper contact support 2, stationary contact tip 19, movable contact tip 22, lower contact support 23, contact bracket 27, terminal 47, shunt 46 and terminal 43 to the 85 other main terminal 44.

It should be noted that the shunt 46 is not attached to the movable contact tip 22, as is customary practice in the prior art. Consequently, during the closing operation of the 90 switch, from the moment the contact tips touch until the switch is fully closed, current is carried from the ear 40 of the movable contact bracket 27 through the pivot 26 and the bracket arms 34 and 35. When the switch is closed, however, the current is carried directly through the abutting contact surfaces of the support 23 and the bracket 27.

The magnetic circuit including the pole pieces for the switching device is also shown in Fig. 1 and Fig. 2. A pair of fan-shaped members 54 and 54^a of magnetizable material are secured to the vertical faces of the arc-chute device 8, and a relatively wide 105 strap member or yoke 55 is riveted to the pole piece 54 on the same side of the switching device as the main terminal 44. Above its riveted end, the strap 55 is provided with an offset bend 55^a, while across the top of 110 the switching device the yoke 55 comprises a horizontal portion 56 which terminates in a downwardly-extending arm 57 for supporting near its lower end a portion 58 of the core member 51 for the blow-out coil 50. 115

A small supporting yoke 59 is provided with a plurality of openings 60 and 61 through which extend wing nuts 62 and 63 for supporting the different parts of the arc-chute device 8. The yoke 59 is, in turn, 120 secured to the upper horizontal portion 56 of the strap 55 by means of a plurality of rivets 64. For the purpose of supporting the entire pole-piece structure near the upper portion thereof, a bent strap 65 is likewise riveted to the horizontal section 56, 125 and is attached to the base 1 by means of a horizontally-extending bolt 66. A further support for the illustrated pole-piece structure is provided by a bent strap 67, which 130

is riveted to the main strap 55 at an intermediate point of the vertical wall 57, the strap 67 being suitably bolted to the base 1.

The core 51 extends through the blow-out coil 50 and is enclosed on the other side of the coil by a plurality of suitable washers or collars 74, which fill the space between the blow-out coil and the fan-shaped pole piece 54^a that is located contiguous to a vertical wall 71 of the arc-chute 8. A sheet 76 of suitable insulating material is preferably located between the washers 74 to prevent the arc formed by the separation of the contact members from spreading to the magnetic blow-out coil.

The arc-chute device 8 comprises a plurality of thin vertical walls 68 and 69 which bear outwardly against the fan-shaped pole-pieces 54 and 54^a, together with a lower spacing member or bridge 71 and two upper spacing members 72 and 77. The arc-chute fits within the pole-pieces and encloses the contact tips 19 and 22, as indicated by the contour of the wall 69 in Fig. 1. The major portion of the arc-chute device 8 is supported by means of the wing-nut 62 that extends through the spacing member 77 of the arc-chute.

The spacing members 71 and 77 are secured to the vertical walls 68 and 69 by means of suitable screws 78 and 79, respectively, while the spacing member 72 may be entirely detached from the vertical walls. The member 72 has its lower end fitting within a notch 73 of the upper contact support 2, and the other end of the member 72 is detachably secured to the vertical walls 68 and 69 and to the supporting yoke 59 by means of the wing-nut 63. In this way, by loosening the wing-nuts 62 and 63 and withdrawing the associated screws, the arc-chute device 8, with the exception of the spacing member 72, may be removed as a unit.

The actuating mechanism 9 comprises a yoke member 80 which is shown in detail in Figs. 7, 9 and 10. A sheet of insulating material 81 is located between the yoke 80 and the insulating block 32 as additional protection.

A piston stem 82 is screwed into the base 83 of the yoke 80, and a plurality of bolts 85 serve to secure the insulating block 32 to the yoke 80. Consequently, the rigidly assembled piston member includes the piston stem 82, the yoke 80, insulating block 32 and contact bracket 27, all of which act as a single unit.

The yoke 80 is provided with a downwardly extending arm 84, having a rectangular slot 84^a for engaging a corresponding-⁶⁰ly shaped lug on the side of the actuating cylinder casing, whereby the piston rod may be guided in addition to the guidance there-⁶⁵of by the internal walls of the cylinder proper; and, furthermore, whereby an

auxiliary contact member, forming one element of the familiar electrical interlock, may be secured to the arm 84 through bolt holes 86, as hereinafter more fully described.

The operating cylinder proper 87 encloses a suitable piston 88 which is rigidly assembled upon the piston stem 82 by means of a nut and washer device 89. A coil spring 90 encloses the piston stem 82 within the cylinder 87 to bias the piston 88 towards the illustrated lower position and thus also bias the movable contact tip 22 towards the illustrated open position.

A suitable air passage 91 effects communication between the cylinder 87 and an electromagnetically-controlled valve 92 which is of familiar construction and, consequently, need not be described in detail here. In general, the valve plugs are secured to a movable core 93 which is surrounded by a coil 94, the core 93 being attached to an armature 95, while a suitable cap 96 covers the top end of the device and serves to secure it to the cylinder casting.

An insulating block 97 is secured to the yoke arm 84 by means of the bolt holes 86 and carries a contact strip or segment 97^a which is adapted to be engaged by a plurality of stationary control fingers 98 when the switch occupies its closed position, wherein the contact block 97 is raised along with the piston and the main movable contact tip. The control fingers 98 are secured to an insulating block 99 which is bolted to the cylinder casting 87. A sheet 100 of insulating material is inclined downwardly from the lower inside corner of the contact block 99 to serve as further insulation of the terminals 101 for the control fingers 98.

The operation of my switching device from the illustrated open position to the closed position may be set forth as follows. Upon energization of the actuating coil 94 for the valve 92, the valve is opened to admit fluid pressure from any suitable source (not shown) to the operating cylinder 87 beneath the piston 88. The piston is thus raised to its uppermost position, carrying the rigidly connected members 80, 81, 32 and 27 therewith. Thus, the reciprocating power element extending from the piston nut 89 to the contact bracket 27, inclusive, acts as a unit by reason of the rigid assembly of the parts named.

The upward movement of the contact bracket 27 likewise raises the contact support 23 and the movable contact tip 22 until the initial contacting between the tips 22 and 19 is effected. The coil spring 43, acting between the contact support 23 and the contact bracket 27, is then gradually compressed as the support 23 pivots around the pin 26. In this way, a combined rolling and wiping contact between the tips 19 and 22 is secured as the piston 88 rises to its upper-¹²⁰¹²⁵¹³⁰

most position accompanied by the gradual compression of the coil spring 43.

During the opening movement of the switch caused by the de-energization of the actuating coil 94, the reverse movements occur, as will be understood, and the arc formed by the separation of the contact tips follows the arcing horns 21 and 25 and is dissipated in the arc-chute 8.

10 I do not wish to be restricted to the specific structural details or arrangement of parts herein set forth, as various modifications thereof may be made without departing from the spirit and scope of my invention. I desire, therefore, that only such limitations shall be imposed as are indicated in the appended claims.

I claim as my invention:

1. In a switching device, the combination 20 with a reciprocatory power element, of an insulating member rigidly secured to one end thereof, a bracket member rigidly secured to said insulating member, and a contact member pivotally mounted on and 25 mechanically interlocking with said bracket member.

2. In a switching device, the combination with a reciprocatory power element, of an insulating member rigidly secured to one 30 end thereof, a bracket member rigidly secured to said insulating member and having a plurality of parallel-extending arms, a contact member pivotally mounted between said arms, and resilient means interposed 35 between said bracket member and said contact member.

3. In a switching device, the combination 40 with a reciprocatory power element, of an insulating member rigidly secured to one end thereof, a bracket member rigidly secured to said insulating member, said bracket member having a pair of parallel-extending arms and a web extending between them for a certain distance, a contact member 45 pivotally mounted between said arms above said web, a spring interposed between said bracket member and said contact member, and a lug on said contact member co-operating with said web to restrict the action of 50 said spring.

4. In a switching device, the combination 55 with a reciprocatory power element, of an insulating member rigidly secured to one end thereof, a bracket member rigidly secured to said insulating member, a contact member pivotally mounted on said bracket member, and a conductor-holding terminal member directly secured to said bracket member.

60 5. In a switching device, the combination 65 with a reciprocatory power element, of an insulating member rigidly secured to one end thereof, a bracket member rigidly secured to said insulating member, said bracket member having a pair of parallel-extending

arms, a web extending between them for a certain distance and an ear extending transversely to said arms, a contact member pivotally mounted between said arms above said web, a spring interposed between said bracket member and said contact member, a lug on said contact member co-operating with said web to restrict the action of said spring, and a terminal secured to said ear.

6. In a switching device, the combination 75 with a reciprocatory power element, of an insulating means rigidly secured to one end thereof, and a contact member pivotally mounted on said insulating means and having an integral projection located to prevent 80 flare-backs of arcs formed by movement of said contact member.

7. In a switching device, the combination 85 with a reciprocatory power element, of an insulating member rigidly secured to one end thereof, a bracket member rigidly secured to said insulating member, a contact member including a removable tip pivotally mounted on said bracket member and having an integral projection located below and 90 substantially parallel to the contacting surface, and an arc horn attached directly to said tip.

8. In a switching device, the combination 95 with a base, of a plurality of co-operating contact members, a blowout coil therefor, a magnetic circuit for said coil including a yoke extending across the top of the switching device, an arc chute for said contact members, means for detachably securing said arc-chute to the top portion of said yoke, and means for attaching said yoke to 100 said base.

9. In a switching device, the combination 105 with a vertically-extending base, of a plurality of co-operating contact members, a blowout coil and an arc-chute therefor, a magnetic circuit for said coil including pole-pieces extending along the sides of said arc-chute, a core for said coil, a yoke member 110 extending upwardly from one pole-piece, across the top of the switching device and downwardly to said core, means for securing said arc-chute to the top portion of said yoke, and means for attaching said yoke to 115 said vertically extending base.

10. In a switching device, the combination 120 with a reciprocatory power member including a conducting bracket member, a contact member pivotally mounted on said bracket member, means for normally separating confronting surfaces of the bracket and the contact members, said surfaces directly abutting under closed conditions of the switching device to carry current.

11. In a switching device, the combination 125 with a reciprocatory power element, of an insulating member rigidly secured to one end thereof, a bracket member rigidly secured to said insulating member and having 130

- a plurality of parallel-extending arms, a contact member pivotally mounted between said arms, a spring interposed between said bracket and said contact members to normally separate confronting surfaces thereof, and a flexible conductor secured to said bracket member, whereby under preliminary closing conditions of the switching device
- current is carried from said conductor through the pivotal connection, while under ¹⁰ closed conditions of the device, said surfaces directly abut to carry current.

In testimony whereof, I have hereunto subscribed my name this 31st day of July, 1919.

ANDREW H. CANDEE.
